United States Patent Office.

RUFUS E. BEAN, OF FRANKLIN, NEW HAMPSHIRE.

Letters Patent No. 93,040, dated July 27, 1869.

IMPROVED DEVICE FOR SUSPENDING PICTURE-FRAMES AND MIRRORS.

The Schedule referred to in these Letters Patent and making part of the same.

To all whom it may concern:

Be it known that I, RUFUS E. BEAN, of Franklin, in the county of Merrimack, and State of New Hampshire, have invented a new and improved Method of Hanging Picture-Frames; and I do hereby declare that the following is a full and exact description of the same, reference being had to the accompanying drawings, and to the letters of reference marked thereon.

This invention relates to an improved method of suspending picture-frames at any desired angle; and consists in attaching a corrugated piece of wire vertically at each side of the back of a picture-frame, as will hereinafter more fully appear.

To enable others skilled in the art to make and use my invention, I will now describe its construction and operation, reference being had to the accompanying drawing, showing a side elevation of the same.

A represents the frame, to the back of which are attached vertically, the corrugated wire pieces B, which may be of any desired length, and are secured at the ends by screws.

A sufficient space is left between the wire and the back of the picture to admit of the cord C passing between them. The cord C is placed in corresponding corrugations on each side of the frame, and, when de-

sired, may be placed higher or lower, by simply slipping it between the frame and the inner corrugations.

The picture-frame may thus be hung at any desired angle, as when the cord is attached nearer the centre of gravity, the frame will hang at a greater angle with the wall, and when the cord is raised, the angle will become less in proportion to the point to which the cord is raised.

It will be readily seen that this is an exceedingly simple, cheap, and effective device, obviating the necessity of rings or staples, which admit of but one angle, and require to be moved when a different one is desired.

Having thus fully described my invention, What I claim as new, and desire to secure by Letters Patent, is—

The corrugated wire B, when used in connection with the frame A and cord C, substantially as described and shown, for the purpose set forth.

This specification signed and witnessed, this 3d day of May, 1869.

RUFUS E. BEAN.
